HOIST

Frank Lock, Philadelphia, Pa., assignor to The
Yale & Towne Manufacturing Company,
Stamford, Conn., a corporation of Connecticut

Application January 24, 1940, Serial No. 315,355

6 Claims. (Cl. 254—173)

This invention relates to hoisting mechanism, and more especially to a hoist of the type in which there is employed a drum having a spiral groove into which is wound a wire rope or cable.

More particularly, my invention relates to a combined rope guide and limit switch for a hoist of the class described. My invention also provides means for adjusting the rope guiding mechanism and the limit switch mechanism whereby to contribute much sought-for results.

More in detail, my invention provides a rope guiding member which is mounted for sliding movement on a shaft parallel to the axis of the hoisting drum, there being provided limit switches adjacent each end of the drum which are actuated by a portion of the rope guiding member, this portion being preferably cast integrally with the rope guiding member. By mounting the limit switches for adjustment preferably parallel to the movement of the rope guiding member, I make it possible to operate the limit switches by the rope guiding member in any position to which they are adjusted. The adjustment is exceedingly simple, as is apparent, and may be made practically in an unlimited number of positions.

As a further feature of my invention, I so mount the rope guiding member that it itself is adjustable relatively to its mounting means to bring it into proper cooperating relation with the rope and winding drum. Preferably, the means which are utilized comprise an eccentric sleeve mounted between the shaft which supports the rope guiding member and the rope guiding member itself, it being obvious that rotation of this eccentric sleeve will adjust the rope guiding member.

For a detailed description of a preferred embodiment of my invention, I shall refer to the drawings wherein Fig. 1 is a perspective view of 40 a hoist in which my invention is embodied. Fig. 2 is a section along lines 2—2 of Fig. 1, while Fig. 3 is a section along lines 3—3 of Fig. 1. Figs. 4 and 5 are sections along lines 4—4 and 5—5, respectively, of Fig. 2. Fig. 6 is a section along lines 6—6 of Fig. 4. Fig. 7 is a perspective view of my rope guiding member taken on an angle substantially opposite the angle of Fig. 1.

Referring now more particularly to the drawings, I show in Fig. 1 a form of wire rope hoist in which there is utilized a lifting drum 10 having formed therein a spiral groove 11 into which is adapted to enter a wire rope 12. The rope 12 may be secured to the drum in any one of several ways known in the art, and as the drum rotates, the wire is wound into the groove, all as will be appreciated by those skilled in the art.

For rotating the winding drum, I utilize a motor mounted in the housing 13 and rotating the drum through suitable gears in the housing

14. A shaft 15 is secured parallel to the axis of the winding drum 10 and supports thereon in a manner to be described presently, a rope guiding member 16. This rope guiding member 16 has a relatively long forward leg 17 and a shorter forward leg 18, it being the function of a portion of the longer leg 17 to ride in the groove 11 in advance of the wire rope 12, as is best shown in Fig. 5, thereby moving the rope guiding member 16 and guiding the rope into the groove 11. Actually, it is the surface 17a of the longer leg 17 which lies in the groove 11.

The rope guiding member 16 has a further portion 19 similar to portion 17a and riding in a portion of the groove 11 somewhat behind the portion 17a, and assisting the portion 17a in moving the rope guiding member, as will be appreciated.

The rope 12 is guided by the legs 17 and 18 of 20 the rope guiding member 16 into the groove 11, and a flat spring member 20 (Figs. 4 and 7) which is sufficiently wide to overlap two juxtaposed groove portions of the spiral groove 11, assists in maintaining the rope 12 in position. It will now be obvious that rotation of the drum will cause a movement of the rope guiding member 16 on its shaft 15 to guide the rope into and out of the spiral groove 11 of the drum 10, depending upon the direction of rotation of the drum 10.

I employ a novel construction for adjusting the rope guiding member 16 relatively to the remainder of the hoist, it being obvious that such adjustment may become necessary, especially as the hoist wears. For the particular purpose, I interpose between the cylindrical portion 21 of the rope guide member 16 and the shaft 15 an eccentric sleeve 22, best shown in Figs. 4 and 6. One end of this eccentric sleeve 22 has a hexagon head 23 whereby the sleeve may be rotated to adjust the relationship between the cylindrical portion 21 of the rope guiding member 16 and the shaft 15, all as will be quite apparent.

For maintaining the sleeve 22 in any adjusted position and against movement relatively to the cylindrical portion 21 of the rope guiding member 16, I utilize a bolt 24 screw threaded into an offset portion extended from the cylindrical portion 21. When this bolt is tightened, it acts through the washer 26 to secure the hexagon head 23 of the sleeve 22 against any rotation whatsoever. It is thought that the construction of the adjusting sleeve and its manner of operation will now appear quite clear.

55 A pair of brackets 27 extending from the main body of the hoist support an open casting 28 in which are housed an upper limit switch 29 and a lower limit switch 30. Since these switches are identical in construction, mounting and operation, only the lower limit switch will be described

in detail. The wiring of the switches and their relation to the hoisting motor circuit is not here shown since that is not part of the invention, being similar to that of the usual paddle operated limit switches well known by those skilled in the art.

Referring now particularly to Figs. 1-3, it will be noted that within the open casing 28 there is a longitudinally extending box-like bracket 31 slotted as at 32 for the passage of the headed bolts 33 maintained in threaded engagement with a threaded plate 34 held within the box-like bracket 31. The limit switch 30 is supported by L-shaped brackets 35, each of which is bored for the passage of the headed bolts 33. It is obvious that by loosening the bolts 33 relatively to the threaded plate 34, it is possible to slide the limit switch 30 and plate 34 relatively to the bracket 31 and into any particular adjusted position.

Each limit switch is equipped with a push button 36, and this push button is adapted for operation by an arm 37 extending upwardly from the rope guiding member 16, and preferably integral therewith. It is obvious that in the lowered position of the hoist, the arm 37 will actuate the push button 36 of the lower limit switch 30, while when the load is raised, the arm 37 will actuate the push button 36 of the upper limit switch 29. It is obvious further that because of the manner in which the adjustments are made in the position of the lower limit switch, and of course of the upper limit switch, the arm 37 will operate the switches quite effectively in any adjusted position.

While I have shown a preferred embodiment of my invention, it is obvious that many other forms thereof incorporating my contribution to the art will be readily conceived by those skilled in the art. I shall therefore claim a monopoly of such breadth as to prevent the utilization of my contribution by others.

I claim:

1. In a hoist of the class described, a rotating drum having a spiral grooved surface, a hoisting rope adapted for spiral winding in the groove of said surface, a rope guiding member having a portion fitting into the groove of said drum, a shaft parallel to the axis of said drum and about which said member is mounted for sliding movement, which sliding movement is imparted to said member through said portion by rotation of said drum, means whereby said member guides the rope into said drum as the drum rotates, an electric switch positioned at each end of said drum, means forming part of said rope guiding member for actuating one switch when said rope guiding member moves to one end of said drum, and for actuating the other switch when said rope guiding member moves to the other end of said drum, and an eccentric sleeve imposed between said rope guiding member and said shaft, rotation of said sleeve relatively to said rope guiding member acting through said eccentric to adjust the position of said member and its groove engaging portion, relatively to said shaft.

2. In a hoist of the class described, a rotating drum having a spiral grooved surface, a hoisting rope adapted for spiral winding in the groove of said surface, a rope guiding member, a shaft parallel to the axis of said drum and about which said member is mounted for sliding movement, means whereby rotation of said drum imparts sliding movement to said member, an eccentric sleeve imposed between said rope guiding mem-

ber and said shaft, rotation of said sleeve relatively to said rope guiding member acting through said eccentric to adjust the position of said member on said shaft and relatively to said drum.

3. In a hoist of the class described, a rotating drum having a spiral grooved surface, a hoisting rope adapted for spiral winding in the groove of said surface, a rope guiding member having a portion fitting into the groove of said drum, a shaft parallel to the axis of said drum and about which said member is mounted for sliding movement, which sliding movement is imparted to said member through said portion by rotation of said drum, an eccentric sleeve imposed between said rope guiding member and said shaft, rotation of said sleeve relatively to said rope guiding member acting through said eccentric to adjust the position of said member and its groove engaging portion relatively to said drum.

4. In a hoist of the class described, a rotating drum having a spiral grooved surface, a hoisting rope adapted for spiral winding in the groove of said surface, a rope guiding member having a portion fitting into the groove of said drum, a shaft parallel to the axis of said drum and about which said member is mounted for sliding movement, which sliding movement is imparted thereto through said portion by rotation of said drum, a sleeve fitted on said shaft and having a circular surface eccentric relatively to said shaft, said rope guiding member being mounted on said shaft through the intermediary of said circular surface, and means for rotating said sleeve on said shaft to adjust the position of said member and its groove engaging portion relatively to said drum.

5. In a hoist of the class described, a rotating drum having a spiral grooved surface, a hoisting rope adapted for spiral winding in the groove of said surface, a rope guiding member having a portion fitting into the groove of said drum, a shaft parallel to the axis of said drum and about which said member is mounted for sliding movement, which sliding movement is imparted thereto through said portion by rotation of said drum, an eccentric sleeve imposed between said rope guiding member and said shaft, rotation of said sleeve relatively to said rope guiding member acting through said eccentric to adjust the position of said member and its groove engaging portion relatively to said drum, and means for securing said sleeve and rope guiding member for movement as a unit on said shaft.

6. In a hoist of the class described, a rotating drum having a spiral grooved surface, a hoisting rope adapted for spiral winding in the groove of said surface, a rope guiding member having a portion fitting into the groove of said drum, a shaft parallel to the axis of said drum and about which said member is mounted for sliding movement, which sliding movement is imparted thereto through said portion by rotation of said drum, a sleeve fitted on said shaft and having a circular surface eccentric relatively to said shaft, said rope guiding member being mounted on said shaft through the intermediary of said circular surface, means for rotating said sleeve on said shaft to adjust the position of said member and its groove engaging portion relatively to said drum, and means for securing said sleeve and rope guiding member for movement as a unit on said shaft.
